UNITED STATES PATENT OFFICE.

JOSEPH F. DWYER, OF SEATTLE, WASHINGTON.

DEVICE FOR DISPENSING TICKETS.

1,332,386.

Specification of Letters Patent. Patented Mar. 2, 1920.

Application filed May 16, 1919. Serial No. 297,682.

To all whom it may concern:

Be it known that I, JOSEPH F. DWYER, a citizen of the United States, residing at Seattle, in the county of King and State 5 of Washington, have invented a certain new and useful Improvement in Devices for Dispensing Tickets, of which the following is a specification.

My invention relates to improvements in 10 devices for dispensing tickets, labels and the like and the object of my invention is to provide a device that is simple in its plan of construction, efficient in its operation and inexpensive to manufacture.

15 A further object is to provide a device for dispensing tickets, labels and the like that may be constructed in single units and that are particularly adapted to be assembled in side by side relation to form a 20 compact ticket dispensing device of any desired number of units.

A still further object resides in the provision of means whereby access to the interior of any one of the units of a multiple 25 ticket dispensing device may be gained without disturbing the other units of such device.

With the above and other objects in view 30 my invention consists in the novel construction, adaptation and combination of parts of a device as will be more clearly herein-after described and claimed.

I accomplish these objects by devices illustrated in the accompanying drawings, 35 wherein—

Figure 1 is a view in vertical cross-section of a ticket dispensing device constructed in accordance with my invention;

Fig. 2 is a plan view of the same;

40 Fig. 3 is a sectional view on broken line 3, 3 of Fig. 1;

Fig. 4 is a view in rear elevation of a multiple ticket dispensing device composed of three units shown in Fig. 1;

45 Fig. 5 is a view partly in cross-section and partly in plan of a modified form of my invention with one side removed; and

Fig. 6 is a view partly in plan and partly 50 in cross-section of the removed side of the device shown in Fig. 5.

Referring to the drawings throughout which like reference numerals indicate like parts, the numerals 7 and 8 designate two disks, preferably of sheet metal, that form 55 the end walls of a ticket dispensing device and 10 designates a substantially semicir-

cular circumferential wall section that is rigidly secured at its two edges to the peripheral portions of the end disks 7 and 8 and serves to hold such disks in rigid spaced 60 apart relation.

The half of the circumferential wall opposite the fixed wall section 10 is formed by a substantially semi-circular swinging wall section 11 that is hinged as at 12 to the 65 lowermost end of the fixed section 10 and is arranged to swing rearwardly as indicated by dotted lines in Fig. 1 to afford access to the interior of the ticket dispensing device and permit ticket ribbon 13 to be inserted 70 therein.

The upper end of the fixed wall section 10 is rounded as at 14 to form a guide member for the ticket ribbon and is thence extended outwardly and downwardly in the form of 75 a shallow channel shaped shelf 15 upon which the ticket ribbon may rest and over which it may pass. The outer end of the shelf 15 is notched as at 16 to facilitate grasping the end of the ticket ribbon with 80 the fingers.

The uppermost end of the swingingly mounted wall section 11 is flattened as at 17 so that it projects substantially tangentially from the wall section 11 and is adapted to 85 rest on the upturned edges of the shelf 15 as more clearly shown in Fig. 3. The central portion of the flattened end 17 is cut away as at 18 and has a transparent plate 20 secured thereover as by a retaining member 90 21 so that the end of the ticket ribbon is visible as it lies on the shelf 15.

If desired means may be provided for locking the swinging wall section 11 in a closed position. 95

The swinging wall section 11 is provided near its upper end with a tension spring 22 having a free outer end that is arranged to rest on the ticket ribbon 13 at the point where it passes over the guide member 14 100 to restrain such ribbon from pulling outward easily and to prevent such ticket ribbon from being pushed back into the receptacle after it has been pulled outwardly past the end of the tension spring 22.

The fixed wall section 10 may have a rigid base bracket 23 of any convenient form that may be secured by bolts 24 to any suitable support or base block 25.

In the form of device above described the 110 sides are flat and without projections of any form so that any number may be arranged in

side by side relation as shown in Fig. 4 to form a multiple ticket dispensing device and the swinging wall sections 11 are constructed and arranged so that they may be operated 5 freely and independently to open and close the several units when a plurality of such units are assembled.

By the foregoing description it will readily be seen that where this form of construction is employed it is not necessary to construct ticket dispensing devices of different sizes to meet different requirements but it is only necessary to assemble the desired number 10 of units into a multiple ticket dispensing device that will accommodate any desired 15 number of ticket ribbons.

The ticket ribbon lies freely within the device and may easily be inserted within when the swinging wall section 11 is in an open 20 position, the end of the ribbon being laid on the shelf 15 in the proper position before the swinging wall section 11 is closed.

In Figs. 5 and 6 I have shown a ticket ribbon dispensing device comprising a cylindrical shell 26 having one permanent end wall 27 and one removable end wall 28, such device being provided with mechanism indicated at 29 and substantially the same as shown in Fig. 1 through which ticket ribbon may 25 be extracted. The removable end wall 28 is shown as provided with a flange 30 that may be inserted within the cylindrical shell 26, that portion of the flange 30 opposite the extracting devices 29 being removed as indicated at 31. The operation of the device 30 shown in Figs. 5 and 6 is substantially the 35

same as the operation of the device shown in Figs. 1 to 4 inclusive except that the ticket ribbon is inserted through the side and it is not so well adapted for multiple 40 use.

Obviously changes in the precise form of construction and arrangement of the various parts of my invention may be resorted to without departing from the spirit thereof. 45

What I claim is:

A device of the class described comprising two rigid end walls; a rigid circumferential wall section extending substantially one half of the distance around the peripheries of said two end walls and uniting said end walls; an integrally formed guide member at the top end of said fixed circumferential wall; an integral channel shaped shelf projecting outwardly and downwardly from 50 said guide member; a swinging circumferential wall section hinged to the lowermost end of said rigid circumferential wall section and arranged to be opened to afford access to the interior of said device, said 55 swinging circumferential section having a flattened end portion arranged for the reception of a transparent plate and adapted to rest upon the edges of said channel shaped shelf; and tension means carried by said 60 swinging circumferential wall section and arranged to engage ticket ribbon that may 65 pass over said guide roll.

In witness whereof, I hereunto subscribe my name this 9th day of May A. D. 1919.

JOSEPH F. DWYER.
